UNITED STATES PATENT OFFICE.

WILLIAM A. E. HENRICI, OF ROXBURY, MASSACHUSETTS, ASSIGNOR TO HENRICI
WASHING MACHINE COMPANY, A CORPORATION OF MASSACHUSETTS.

WASHING-MACHINE.

1,309,412.

Specification of Letters Patent.

Patented July 8, 1919.

Application filed December 22, 1916. Serial No. 138,480.

To all whom it may concern:

Be it known that I, WILLIAM A. E. HENRICI, a citizen of the United States, residing at Roxbury, county of Suffolk, and 5 State of Massachusetts, have invented an Improved Washing-Machine, of which the following is a specification, reference being had to the accompanying drawings, forming part thereof.

10 This invention has reference to improvements in washing machines and more particularly to improvements in washing machines of the character described in my co-pending application Serial No. 105,917, filed 15 June 26, 1916.

The main object of the invention is to provide improved means, of simple construction and operation, for discharging the fluid contents from the wash-tank of washing machines of this character.

Other objects of the invention will appear from the following description.

The invention consists in such novel features of construction, operation and combination of parts as shall hereinafter be described and pointed out in the claims.

Referring to the drawings:—

Figure 1, represents a front view in elevation of a machine embodying my invention 30 with parts broken away to save space and parts in section.

Fig. 2, represents a sectional view taken on the line 2—2 of Fig. 1.

Fig. 3, represents a sectional view taken 35 on the line 3—3 of Fig. 1.

Fig. 4, represents a view similar to a portion of Fig. 3 with parts shown in a different position.

Fig. 5, represents a sectional plan view 40 taken on the line 5—5 of Fig. 3.

Fig. 6, represents a sectional view taken on the line 6—6 of Fig. 3.

Fig. 7, represents a sectional view taken 45 on the line 7—7 of Fig. 6.

Figs. 8 and 9, represent sectional views respectively taken on lines 8—8 and 9—9 of Fig. 7.

Fig. 10, represents a sectional view taken on line 10—10 of Fig. 3.

50 Like characters of reference designate corresponding parts throughout.

The machine shown in the drawings is provided with the usual frame 10 having the standards 11 and 12. On the upper ends 55 of the latter are respectively journaled the

trunnions 13 and 14 projecting from the cylindrical wash-tank 15, transversely to the longitudinal center line thereof. Said wash-tank may be rotated from any suitable source of power, through the worm-wheel 17 on the outer end of the trunnion 13, and the worm 18 mounted on the standard 11. Washing fluid and steam may be circulated through said wash-tank as described in my said co-pending application, the outlet pipes 60 20 and 21 connecting the respective ends of said wash-tank to a common outlet passage in the trunnion 14. On one end of said wash-tank 15 is the door 22 held closed by the pivoted eye-bolts 23. The other end of 65 said wash-tank is closed by the head 24 secured to the inside thereof. Said head 24 is provided with the valve chamber 25, the inner side of which is covered by the circular perforated plate or screen 26. Secured 70 to the upper side of the latter is the series of perforated semispherical hollow knobs 27. In the valve chamber 25 are the four valves 28, provided with valve stems 29 mounted to slide in bearings 30 in said head 24. Said 75 valves are normally held to close their respective valve openings 31 in said head by the expansion springs 32 on said valve stems which bear against the ends of said bearings 30 and the shoulder 33 on said valve stems. 80 Said valve openings 31 lead into one end 35 of the exhaust chamber 36 secured at said end to said head 24. Said exhaust chamber consists of the outlet pipe 37 and the annular chamber 38 secured thereto and which surrounds the trunnion 13. Said outlet pipe 85 and said annular chamber are in communication through the opening 39. Said annular chamber is further provided with the opening 40 and is inclosed by the casing 41 90 at the upper end of the discharge pipe 42 which leads to the tank 43. Leaking from the bottom of the latter is the drain pipe 44. Mounted to slide on the stud 47 projecting 95 from the head 24 is the cross-head 49 adapted to engage the ends of the valve stems 29. The pair of arms 50 connect said cross-head to the rock shaft 51 which is journaled in the hanger 52 projecting from the head 24; the stuffing-box and bearing 53 in the end 100 35 of the outlet pipe 37; and the hanger 54 projecting from the head 24. On the outer end of the rock-shaft 51 is the arm 55 pivoted on one end of the rod 56. The upper end 105 of the latter extends through and is guided 110

by the bracket 57 projecting from the wash-tank 15. Pivoted on said bracket is the bell-crank lever 58, the lower end of one arm 59 of which is forked to straddle said rod 56 and is pressed toward the latter by the spring pressed plunger 60 which engages the other arm of said bell-crank lever. On said arm 59 and said rod 56 are the coöperating locking shoulders 61 and 62 respectively. Carried by said rod is the roller 63 adapted to engage the top surface 64 of the cam lever 65 and the end of the arm 59 of the bell-crank lever 58 is adapted to engage one of the inclined surfaces 66, 66 of said cam lever. The latter is pivoted at one end 67 on said standard 12 and the other end of said cam lever is connected to the crank-arm 70 by the link 71. Said crank arm is on one end of the short shaft 72 extending through standard 12 and on the other end of said shaft is the arm 73 provided with the handle 74 at right angles thereto. Said arm 73 is adapted to be engaged by the lower end of the locking-lever 75 pivoted at 76 and having its upper end held in engagement with the cam 77 on the valve stem 78 of the valve 79, by the expansion spring 80 on the stud 81 bearing against the inside of standard 12. Said valve 79 is on the air vent pipe 82.

When it is desired to discharge the fluid contents of the wash-tank 15, the flow of the washing fluid and steam into said wash-tank is first shut off and the valve 79 opened. The opening of said valve causes the cam 77 to swing the lower end of the locking lever 75 out of engagement with the arm 73 against the action of the spring 80. The arm 73 is then swung by hand from its normal position shown in Fig. 3 to the position shown in Fig. 4, which, through the connecting elements, raises the cam lever 65 on its pivot to the position shown in the latter figure.

When the roller 63 is then brought into engagement with the top surface 64 of said cam lever, by the rotation of said wash-tank, it will be raised thereby, which, in turn, will raise the rod 56 sufficiently to allow the locking shoulder 61 to engage the locking shoulder 62 by the action of the spring pressed plunger 60, thereby locking said rod in its raised position as shown by dotted lines in Fig. 10.

The raising of said rod 56 will through the arm 55, rock shaft 51, pair of arms 50 and cross head 49, open the valves 28 against the action of their springs 32. The opening of said valves allows the fluid contents of the wash-tank to rapidly flow into the outlet pipe 37 of the exhaust chamber 36 by gravity and centrifugal force. The outlet pipe 37 is so shaped and positioned in respect to the direction of rotation of said wash-tank that as the receiving end 35 of said outlet pipe is raised, the fluid will flow therethrough

and enter the annular chamber 38. Approximately at the completion of one half a revolution of said wash-tank from the position shown in Fig. 3, the outlet pipe 37 and annular chamber 38 will have received 70 its maximum amount of fluid contents from said wash-tank, at which time the opening 40 will be brought to register with the receiving end of said discharge pipe 42, allowing said fluid contents to be discharged into 75 said tank 43, from which it may flow through the drain pipe 44. It is to be noted that the fluid rushes with considerable force both out of the wash-tank and out of said exhaust-chamber which, of course, renovates 80 these parts much more thoroughly and rapidly than though the fluid flowed slowly. The force of the discharging fluid is not only due to its free passage through the comparatively large conduits, but also to the 85 shape of the rearwardly and inwardly extending outlet pipe 37, which, as it revolves, allows centrifugal force and gravity to act to advantage to first discharge the fluid from the wash-tank into said outlet pipe and then 90 out of the latter.

The perforated knobs 27 tend to prevent the wash *w* from stopping the perforations in the plate 26.

When the wash-tank is discharged of its 95 fluid contents and it is desired to furnish a new supply of washing fluid to the tank, the arm 73 is first swung by hand back to its normal position which, through the connecting elements, lowers the cam lever 65 on its pivot to its normal position. (Fig. 3.) When said cam lever is thus set, the continued rotation of said wash-tank will result in the forked end of arm 59 of the lever 58 engaging one of the inclined surfaces 66, 105 causing said arm to retract sufficiently to disengage shoulder 61 from shoulder 62, thereby releasing the rod 56 to allow the springs 32 to close their respective valves 28. The means for supplying washing fluid and 110 steam to said wash-tank is such that this cannot be efficiently done without first closing the air-vent valve 79. The closing of the latter results in the cam 77 swinging locking lever 75 on its pivot to cause the 115 lower end of said locking lever to engage the top of the arm 73, which together with the stop 70^a engaging arm 70, locks said arm 73 in its normal position. The locking of arm 73 while washing fluid and particularly 120 steam is entering the wash-tank is of considerable practical importance in avoiding accidents due to carelessness of the operator. If the arm 73 was positioned to open the discharge valves 28 while steam under a high 125 pressure was in the wash-tank, which of course would tend to close the said valves, some part of the valve operating mechanism would be liable to break and be thrown with considerable force from the rotating wash- 130

tank. In order to discharge the fluid contents of the wash-tank the operator must first relieve the pressure therein. It is to be noted that it is not necessary to stop the 5 rotation of the wash-tank in order to discharge and renew the fluid contents thereof.

Another feature of the machine which is of practical importance in avoiding accidents, is that the valve mechanism will operate as well when the wash-tank is rotated in one direction as in the other, so that should the operator inadvertently start the machine operating in the reverse direction to that indicated by the arrow *a* in Fig. 3, 10 no harm will be done.

While it is preferred to employ the specific construction and arrangement of parts shown and described, it will be understood that this construction and arrangement is 20 not essential except so far as specified in the appended claims, and may be changed or modified without departing from the broader features of the invention.

Having thus described my invention I 25 claim as new and desire to secure by Letters Patent:

1. In a washing machine the combination of a wash-tank, means for imparting a rotary movement thereto, an exhaust chamber 30 in communication therewith, with means for discharging the fluid contents of said wash-tank into said exhaust chamber during the first half of a revolution of said wash-tank and for discharging the said fluid contents 35 from said exhaust chamber during the second half of a revolution of said wash-tank.

2. In a washing machine the combination of a wash-tank, an exhaust chamber in communication and rotatable therewith, with 40 means for discharging the fluid contents of said wash-tank into said exhaust chamber during the first half of a revolution of said wash tank and said exhaust chamber and for discharging the said fluid contents from 45 said exhaust chamber during the second half of a revolution thereof.

3. In a washing machine the combination of an elongated wash-tank, means for rotating said wash-tank on an axis transverse to 50 the longitudinal center line thereof, an exhaust chamber having the receiving end thereof extending rearwardly from one end of said wash-tank, with means for allowing the fluid contents of said wash-tank to pass 55 into said exhaust chamber and for allowing the said fluid contents to pass from said exhaust chamber during one revolution of said wash-tank.

4. In a washing machine the combination 60 of a wash tank, an exhaust chamber in communication and rotatable therewith, a stationary discharge pipe in communication with said exhaust chamber, with valve controlled means for discharging the fluid contents of said wash-tank into said exhaust

chamber and for discharging the said fluid contents from said exhaust chamber into said discharge pipe.

5. In a washing machine the combination of an elongated wash-tank, means for rotating said wash-tank on an axis transverse to the longitudinal center line thereof, an exhaust chamber extending rearwardly from one end of said wash tank and to the said axis, said wash-tank in communication with 70 said exhaust chamber through a valve, with means for opening and closing said valve during the rotation of said wash-tank.

6. In a washing machine the combination of an elongated wash-tank, means for rotating said wash-tank about an axis transverse to the longitudinal center line thereof, an exhaust chamber having one of its ends connected to one end of said wash tank and having its outlet end located around the said 80 axis, a valve for controlling the passage of the fluid contents of said wash-tank into said exhaust chamber, means for opening and closing said valve, said outlet end of said chamber provided with an opening adapted 85 to register with an opening in a discharge pipe after the fluid contents of said wash-tank have passed into said exhaust chamber, substantially as described.

7. In a washing machine the combination 90 of a wash-tank, means for imparting a rotary movement thereto, an exhaust chamber in communication with said wash-tank, a valve for controlling the passage of the fluid contents of said wash-tank into said exhaust 95 chamber, means for opening and sustaining open said valve during substantially a complete revolution of said wash-tank, with means for closing said valve.

8. In a washing machine the combination 100 of an elongated wash-tank, means for rotating said wash-tank about an axis transverse to the longitudinal center line thereof, an exhaust chamber in communication with one end of said wash-tank through a valve in 105 said end, means dependent upon the rotation of said wash-tank for opening said valve, with means for closing said valve.

9. In a washing machine the combination 110 of an elongated wash-tank, means for rotating said wash-tank about an axis transverse to the longitudinal center line thereof, an exhaust chamber in communication with one end of said wash-tank through a valve, means for opening said valve and for locking 115 said valve open during the rotation of said wash tank, with means for releasing said locking means to allow said valve to close.

10. In a washing machine the combination 120 of an elongated wash-tank, means for rotating said wash-tank about an axis transverse to the longitudinal center line thereof, an exhaust chamber in communication with one end of said wash-tank through a normally 125

closed valve, means for opening said valve, means for locking said valve open, with means for releasing said locking means to allow said valve to close.

5 11. In a washing machine of the character described the combination of an elongated wash-tank, means for rotating said wash tank about an axis transverse to the longitudinal center line thereof, an exhaust 16 chamber in communication with one end of said wash-tank through a normally closed valve, means for opening said valve and locking said valve open, with means dependent upon the rotation of said wash-tank for releasing said locking means to allow said valve to close.

12. In a washing machine the combination 20 of an elongated wash-tank, means for rotating said wash-tank about an axis transverse to the longitudinal center line thereof, an exhaust chamber in communication with one end of said wash-tank through a valve, means for opening and closing said valve, with a screen between said valve and the 25 center of said wash-tank, substantially as described.

13. In a washing machine the combination of an elongated wash-tank, means for

rotating said wash-tank about an axis transverse to the longitudinal center line thereof, 30 one end of said wash-tank closed by a head having a plurality of valves therein, with means for simultaneously opening said valves to allow the fluid contents of said wash-tank to pass into an exhaust chamber, 35 with means for closing said valves.

14. In a washing machine the combination of a wash-tank, means for imparting a rotary movement thereto, an exhaust chamber in communication with said wash-tank 40 through a normally closed valve, means for opening said valve, with a safety device for allowing said valve opening means to operate only when pressure in said wash-tank is relieved.

15. In a washing machine the combination of a wash-tank, means for imparting a rotary movement thereto, an exhaust chamber in communication with said wash-tank through a normally closed valve, means for 50 opening said valve, with a safety device, adapted to be connected to the stem of an air vent valve leading into said wash-tank, for allowing said valve opening means to operate only when said air vent valve is open. 55

WILLIAM A. E. HENRICI.
